UNITED STATES PATENT OFFICE.

VICTOR FERNANDEZ, OF GUATEMALA, GUATEMALA.

DESIGN FOR A CABINET-BRUSH.

45,746.

Specification for Design.

Patented May 12, 1914.

Application filed February 16, 1914. Serial No. 819,126. Term of patent 14 years.

To all whom it may concern:

Be it known that I, VICTOR FERNANDEZ, a citizen of Guatemala, residing at Guatemala, in the Province and Republic of Guatemala, have invented a new, original, and ornamental Design for a Cabinet-Brush, of which the following is a specification, reference being had therein to the accompanying drawing, forming part thereof.

The figure is a perspective view of a cabinet brush showing my new design.

I claim:

The ornamental design for a cabinet brush as shown.

In testimony whereof I hereunto affix my signature in presence of two witnesses.

VICTOR FERNANDEZ.

Witnesses:

PROPIRIO GONZALEZ,
RAYMOND SERENO.
